US00D828054S

(12) **United States Design Patent** (10) **Patent No.:** **US D828,054 S**
(45) **Date of Patent:** **** Sep. 11, 2018**

(54) **PILLOW**

(71) **Applicant:** **SHENZHEN LIAN DA
TECHNOLOGY INDUSTRIAL CO.,
LTD.**, Shenzhen, Guangdong (CN)

(72) **Inventors:** **Congyu Chen**, Guangdong (CN);
Congchao Chen, Guangdong (CN)

(73) **Assignee:** **SHENZHEN LIAN DA
TECHNOLOGY INDUSTRIAL CO.,
LTD. (CN)**

(**) **Term:** **15 Years**

(21) **Appl. No.:** **29/592,430**

(22) **Filed:** **Jan. 30, 2017**

(51) **LOC (11) Cl.** **06-09**

(52) **U.S. Cl.** **USPC D6/601**

CLAIM

The ornamental design for a pillow, as shown and described.

DESCRIPTION

FIG. 1 is a front view of the pillow showing our new design;
FIG. 2 is a back view thereof;
FIG. 3 is a left side view thereof;
FIG. 4 is a right side view thereof;
FIG. 5 is a top view thereof;
FIG. 6 is a bottom view thereof;
FIG. 7 is a top perspective view thereof; and,
FIG. 8 is a bottom perspective view thereof.

1 Claim, 5 Drawing Sheets
